UNITED STATES PATENT OFFICE.

RODOLPHUS W. WALKER, OF LAWRENCE, MASSACHUSETTS, ASSIGNOR TO ELIZABETH S. WALKER, OF LAWRENCE, MASSACHUSETTS.

FAN ATTACHMENT.

1,134,495.

Specification of Letters Patent.

Patented Apr. 6, 1915.

Application filed January 22, 1914. Serial No. 813,693.

To all whom it may concern:

Be it known that I, RODOLPHUS W. WALKER, a citizen of the United States, and resident of Lawrence, in the county of Essex and State of Massachusetts, have invented 5 certain new and useful Improvements in Fan Attachments, of which the following is a specification.

The object of the present invention is to 10 provide an attachment for an electric fan whereby a liquid may be vaporized and carried by the air current produced by the fan. The nature of the liquid thus used to impregnate the air current will be varied according to the requirements of the fan. For 15 example, if the fan were located in an auditorium it would be desirable to use an odorament to overcome any unpleasant odor which might be present in the auditorium. The 20 device is also useful for moistening the atmosphere, and could be used to advantage in a room such as a spinning or weaving room where it is desirable to have the air more moist than normal.

25 The invention, therefore, contemplates broadly the idea of using any liquid which is sufficiently volatile to be absorbed by the air current produced by the fan, whether the purpose of the liquid is to moisten the air or to impart an odor to the air.

30 Of the accompanying drawings, which illustrate one form and arrangement of my invention: Figure 1 represents a side elevation of an electric fan of suitable well-known type adapted for the purpose. Fig. 35 2 represents a front elevation of the fan from the plane indicated by line 2—2 of Fig. 1, the fan guard being shown in vertical section and parts of the wicking being omitted in order to show more clearly the attachments which constitute my invention. Fig. 3 represents a cross section through the structure intersected by line 3—3 of Fig. 2.

40 The same reference characters indicate the same parts wherever they occur.

45 My device comprises three main parts, all of which may be readily attached to the usual guard of an electric fan. These three main parts comprise a reservoir 10 for the desired liquid, and wick-holders 11, 11.

The fan blades are indicated at 12, the motor therefor is indicated at 13, and the motor shaft on which the fan is fixed is indicated at 14. The guard, which is of well-known structure, comprises two rings 15 and

16 which are arranged respectively behind the fan blades and in front of the fan blades, said rings being firmly connected by suitable wire members 17 which are bent toward the axis of the fan, as indicated at 18. The fan 60 guard is supported by brackets 19 which are affixed to the motor casing. The structure of the motor, fan and guard is all well known, and my purpose in illustrating and describing the same is to show in what manner my device may be readily attached to the same and to show also in what relation my device is to be arranged.

The reservoir 10 is provided with suitable devices such as spring clips or hooks 20, 20, 70 adapted to be hooked over the top of the ring 15. The wick-holders 11, 11, are provided with spring clips or hooks 21 which are likewise adapted to be sprung over the ring 15. Each wick-holder is of a substantially 75 segmental form, and, as shown, is made of a single piece of wire. The wire is bent to form an open frame, and the ends of the wire, as shown, are twisted together, as indicated at 22, and arranged to engage the front 80 side of the reservoir 10 to hold the reservoir in an upright position. The arrangement of the hooks 20 on the reservoir would cause the reservoir to hang in an inclined position if some means were not provided for holding the reservoir in an upright position, and the twisted ends 22 afford the most convenient means for this purpose.

85 Each wick holder has two series of loops, those of the one series being indicated at 23, 90 and those of the other series at 24. These loops are provided for receiving a relatively long thin wick 25 which may be laced back and forth from one series of loops to the other. The arrangement of the loops permits a variety of arrangements of the laced wicking, but I have shown only one arrangement of lacing. In order to facilitate the lacing operation as much as possible, I prefer to offset the loops 24 from each other, 95 as illustrated by Fig. 3, each alternate loop being offset laterally in one direction and the intermediate loops being offset laterally in the opposite direction. This staggered arrangement results in causing the loops to 100 project away from each other like spurs, and the wicking 25 may therefore be more easily looped over the offset portions.

I prefer to conduct the liquid from the reservoir by wicks 26 of relatively large di- 110

ameter and capacity, and to employ a plurality for each wick-holder 11 in order to carry a sufficient volume of liquid from the reservoir. The reservoir has holes 26" in its 5 ends through which the wicks 26 are led, these holes being preferably shaped so as to be filled as nearly as possible by the wicks. As I have shown only two wicks 26 for each wick-holder 11, the holes are elongated; but 10 if three wicks were used, the holes would preferably be triangular. I prefer to locate the wick-holes at a considerable distance below the top of the reservoir and to fill the reservoir to a level above the holes so that 15 the liquid will flow out through the holes by gravity as well as by capillary action until the level has dropped to the bottoms of the holes. This results in rapid saturation of the wicks throughout their length, 20 and they are thereafter kept saturated by capillary action. As shown by Fig. 3, the stretches of the wick 25 cross each other, and the stretches of the wick 26 are kept apart by the stretches of the wick 25. 25 The crossing of the wick 25 causes the stretches thereof to be held in contact with the wick 26, with sufficient contacting area to enable the liquid to flow by capillary action from the feeding wick 26 to the smaller 30 wick 25. The wicks are arranged at the rear of the fan blades. When the fan is in motion it draws a current of air through the spaces between the numerous stretches of wicks, and because of the relatively great 35 surface area of the wicks the liquid with which the wicks are saturated is evaporated at a relatively rapid rate and the vapor impregnates the air current and is thrown forward by the fan. In order to hold the wick-holders in place, I provide two helical 40 springs 27 which are arranged respectively above and below the fan shaft 14. Each spring is hooked around the two wick-holders and tends to draw the wick-holders toward each other, thereby keeping the spring 45 hooks 21 firmly engaged with the ring 15 and also holding the wick-holders in a substantially transverse plane.

All three of the main parts of the device 50 may be readily attached and detached, and when it is necessary to renew or clean the wicks the same may be quickly accomplished. The device is adapted to be sold separately and is in such form that anyone 55 having a fan substantially like that illustrated may easily attach the device as shown.

I claim:—

1. The combination with a guard ring of a rotary fan, of a reservoir having devices

arranged to embrace the top portion of such 60 ring to support said reservoir, a plurality of wick holders each having devices arranged to embrace such ring below said devices of 65 said reservoir, means for connecting said wick holders to hold the latter in place, and wicking arranged to conduct liquid from said reservoir to the path of air propelled by such fan, the delivery portions of said wicking being supported by said wick holders. 70

2. The combination with a guard ring of a rotary fan, of a plurality of wick holders each having hooks adapted to embrace such ring and each being detachable by unhooking said hooks from said ring, said wick 75 holders being arranged at opposite sides of the center of said ring, one or more springs connecting said wick holders to keep said hooks forcibly against said ring, a reservoir, and wicking arranged to conduct liquid 80 from said reservoir to the path of air propelled by such fan, the delivery portions of such wicking being supported by said wick holders.

3. A device of the character described 85 comprising an open holder having two series 90 of lacing-engaging devices, a lacing member laced back and forth from said devices of one series to those of the other series, a reservoir, and wicking interlaced with said lacing member between said series of devices and extending into said reservoir to feed liquid therefrom. 95

4. A device of the character described comprising an open holder having two series 95 of wick-engaging devices, wicking engaging and held by said devices and extending from said devices of one series to those of the other series, a reservoir, and wicking interlaced with the first-mentioned wicking 100 and extending into said reservoir to conduct liquid from the latter to the first-mentioned wicking.

5. A wick-holder consisting of two stretches of wire each having a series of 105 bends, each of said bends being adapted to hold the bight of a looped member, the portions of wire between said bends of one of said series being offset laterally from each other to facilitate the casting of such member 110 upon the latter bends.

In testimony whereof I have affixed my signature, in presence of two witnesses.

RODOLPHUS W. WALKER.
